FRANK SHOEMAKER, OF WATERLOO, IOWA, ASSIGNOR OF ONE-HALF TO CLIFTON E. DOXEY, OF WATERLOO, IOWA.

DRIFTING-VALVE FOR LOCOMOTIVES.

1,149,960.

Specification of Letters Patent. Patented Aug. 10, 1915.

Application filed July 30, 1914. Serial No. 854,157.

To all whom it may concern:

Be it known that I, FRANK SHOEMAKER, a citizen of the United States of America, and a resident of Waterloo, Blackhawk county, Iowa, have invented certain new and useful Improvements in Drifting-Valves for Locomotives, of which the following is a specification.

My invention relates to improvements in drifting valves for locomotives, and the object of my improvement is to furnish means for automatically supplying low pressure steam to the cylinders, when the locomotive is drifting with the main throttle-valve closed, for the purpose of preserving the lubrication of the cylinders in effective condition, cushioning the pistons and preventing the burning out of the superheater units of superheater locomotives. This object I have accomplished by the means which are hereinafter described and claimed, and which are illustrated in the accompanying drawings, in which:

Figure 1 is a vertical central longitudinal section of my improved drifting-valve for locomotives, showing a part of the lever broken away. Fig. 2 is a like section of said device, showing the movable parts thereof in different positions from those shown in Fig. 1. Fig. 3 is a diagram showing the means of communication between the parts of said drifting-valve, steam-dome and dry-pipe, and the steam-chest of the locomotive.

Similar numerals of reference denote corresponding parts throughout the several views.

I am aware that drifting-valves have been invented to be employed in supplying steam at a low pressure to the cylinders of a locomotive at times when full boiler steam pressure has been cut off by means of the throttle-valve. This low pressure of steam is required in the cylinders at such times in order to keep the cylinders warm, prevent the pumping of cool air thereinto with the resultant congealing of the lubricating oil and consequent undue scoring and wear of the cylinder by the piston-head, and furthermore, to provide steam-cushions between each piston-head and the cylinder-heads.

In practice, the boiler pressure of the locomotive is maintained at a certain maximum while in use, but notwithstanding this, fluctuations in the pressure of the steam are certain to occur, and therefore it is abso-

lutely necessary that a drifting-valve should be operated under all such variations of boiler pressure to maintain at all times approximately the same low steam pressure in the cylinders. My improved drifting-valve is designed to successfully effect this object.

Figs. 1 and 2 show a casting in which is formed a differential cylinder 1 and a parallel cylinder 11 of the ordinary type each supplied with one closed and one centrally orificed head. The differential cylinder contains interior hollows 2 and 8 of different diameters which are adapted to receive the differential heads 4 and 5, respectively of the differential piston, such heads being spaced and connected by means of a central rod 3. The smaller piston-head 4 has a piston-rod 20 extending through the adjacent orificed cylinder-head, and provided on its outer extremity with a rectangular boxing 21 containing a slide 22 in which a pintle 23 is pivotally mounted. The other cylinder 11 contains a reciprocating piston-head 16 provided with a piston-rod 17 movable through the central orifice in the adjacent cylinder-head, and provided on its extremity with a like rectangular boxing 24 containing a slide 25 in which a pintle 26 is likewise pivotally mounted. The numeral 18 denotes a fixed arm on the orificed cylinder head of the cylinder 1, provided with a forked bearing having a pintle 31 on which one extremity of a lever 19 is pivotally mounted. This lever is made up of two like spaced members in which the ends of the pintles 23 and 26 are mounted on opposite sides of the bodies 21 and 24. The other extremity of said lever is formed into a handle for manual use as hereinafter to be described. The numeral 27 denotes a fixed arm projecting from the orificed head of the cylinder 11 and to whose outer end a swinging stop 28 is pivoted on a pintle 32. Said stop has its other end bifurcated with the forks connected by the bar 29. In the position shown in said Fig. 1, the stop 28 has been swung outwardly to engage and hold the lever 19 in its extended position. In this position, the rod 29 prevents the stop 28 from swinging over any farther. In Fig. 2, said stop is shown as moved over out of engagement with said lever.

The numeral 30 denotes an inlet-port in the cylinder 1 in communication with that part of its inner chamber 2 which forms the

interspace of two piston-heads 4 and 5. This port is placed in communication with the steam under boiler pressure in the dome of the locomotive by means of a conduit 38 controlled by a shut-off cock 37 therein. Said cylinder 1 contains an annular passage or channel 15 concentric therewith and separated from its interior hollow by means of a sleeve 36 fitted into the cylinder to cover and form the inner wall of the channel. This sleeve or cylindrical ring 36 is provided with a plurality of like orifices or ports 6 arranged concentrically around it in a single row, spaced from the adjacent cylinder-head, and lying within the path of travel of the larger piston-head 5, so as to be more or less covered thereby variably as said piston is moved. Said cylinder has an outlet port 7 in communication with the channel 15 and also in communication with the dry-pipe 35 by means of a conduit 34. The chambers 9 and 33, located respectively between the left hand ends of the pistons 4 and 16 and the adjacent cylinder heads, are placed in communication by means of a passage 10 formed in the cylinder casting. The numeral 41 denotes an outlet port in the cylinder 11 in communication between said chamber 33 and the outer atmosphere. By these means, air is admitted into said chambers 9 and 33 from without. The numeral 14 denotes a passage leading from the chamber 8 of the cylinder 1 to the chamber 12 of the cylinder 11, and is adapted to transmit low pressure steam from the one to the other. The cylinder 11 has an outlet-port 13 in communication between the chamber 12 and the steam-pipe part 40 by means of a conduit 39. The drifting-valve is mounted on a bracket 42 in the cab of the locomotive.

Operation: Said Fig. 1 shows the positions of the moving parts of the device when the lever 19 is held at its extreme left hand position by means of the stop 28 to cut off communication between the inlet-port 30 and the outlet ports 6. The conduit 34 which leads from the ports 6 and the channel 15 by way of the port 7 to the dry-pipe 35 communicates with said dry-pipe below the shut-off valve of the throttle. It will be seen that when steam is throttled in said dry-pipe, and the stop 28 has been thrown over out of engagement with the lever 19, that the steam, at full boiler pressure, contained in the chamber 2, will operate to push the piston-head 5 to the right on account of the difference in diameters of the two heads 4 and 5. This will cause the piston to travel to the right until the ports 6 are sufficiently uncovered to allow opening enough to maintain the specified low pressure in the cylinders. Steam passing at full boiler pressure through the partially or wholly opened ports 6 into the channel 15, port 7, conduit 34, and dry-pipe 35, will become expanded

in said channels so as to enter the locomotive cylinders at a low relative pressure. The conduit 39 conducts a portion of this low pressure steam from the dry-pipe part 40 back to the interspaces 12 and 8 of the two cylinders 11 and 1, respectively. This low pressure steam not only pushes the piston 16 to the left, but also acts upon the piston head 5 against the opposite full boiler pressure thereon. The areas of the two pistons 5 and 16 have certain relative proportions respectively to the small piston 4 determined suitably to maintain by means of the low steam pressure thereon an approximately unvarying resistance to the full steam pressure upon said head 5. This relation has a ratio which is based upon the boiler pressure ordinarily used as a maximum or working pressure on the locomotive, and the length of the power arm has a relation to the length of the weight arm of the lever 19 such as will suitably magnify the tractive effort or pull exercised by said lever upon the differential piston in the cylinder 1 and such as will sufficiently act upon the larger piston-head 5 in addition to the low steam pressure thereon. The net result is to equalize the action of said differential piston so that under ordinary working pressures of steam in the boiler, a supply of low pressure steam will be furnished the cylinders at low pressures of very slight variation. My device is thus operative to automatically vary the low steam pressure in the cylinders within very slight limits and relatively proportional to the varying boiler pressures, and will thus work effectually under all conditions of use.

Having described my invention, what I claim as new, and desire to secure by Letters Patent, is:

1. A drifting valve for a locomotive, comprising a valve-chamber provided with both inlet- and outlet- ports, movable elements in said chamber, and mechanism without said chamber linked to said elements operatively, said interconnected elements and mechanism being adapted to control the outlet-port of said chamber to automatically relate the pressure of steam delivered by the outlet-port to the pressure of steam received by the inlet-port to maintain the steam delivered by said outlet-port to the cylinder of the locomotive sufficiently above atmospheric pressure as to provide cushioning-means therein without exercising a driving effect on the locomotive.

2. In combination, a differential cylinder, a differential piston therein, said cylinder having an inlet-port in communication between the interspace of the piston-heads and a supply of steam under boiler pressure, and having an outlet-port in the path of travel of the large piston-head, a conduit between said outlet-port and a steam chest, a second

cylinder, a piston therein, the said differential piston having a rod projecting from its small head and the other piston having a rod projecting in the same direction as the first-mentioned rod, a lever having a fulcrum at one extremity and swiveled to both said rods suitably to maintain a desired proportion between the lengths of the weight arm and power arm of the lever, said cylinders having means of communication between the interspace of the large piston-head and the adjacent cylinder-head of the differential cylinder and the interspace of the second-mentioned cylinder between its piston and its cylinder-head on the same side as said other cylinder-head, and said conduit to the steam chest, the said cylinders having means of communication between their other adjacent ends and the atmosphere.

3. In combination, a differential cylinder, a differential piston therein, said cylinder having an inlet-port in communication between the interspace of the piston-heads and a supply of steam under boiler pressure, and having an outlet-port in the path of travel of the large piston-head, a conduit between

said outlet-port and a steam chest, a second cylinder, a piston therein, the said differential piston having a rod projecting from its small head and the other piston having a rod projecting in the same direction as the first-mentioned rod, a lever having a fulcrum at one extremity and swiveled to both said rods suitably to maintain a desired proportion between the lengths of the weight arm and power arm of the lever, and means for removably holding said lever in a certain position, said cylinders having means of communication between the large piston-head and the adjacent cylinder-head of the differential cylinder and the second-mentioned cylinder between its piston and its cylinder-head on the same side as said other cylinder-head and said conduit to the steam chest, the said cylinders having means of communication between their other adjacent ends and the atmosphere.

Signed at Waterloo, Iowa.

FRANK SHOEMAKER.
